[57] ABSTRACT

A relay for the voltage regulator in which a setting voltage for voltage regulation is capable of being easily and accurately adjusted without moving the armature and contacts by providing a movable iron piece for effectively changing the gap between the armature and the yoke.

FIG. 5

RELAY FOR VOLTAGE REGULATOR

FIELD OF THE INVENTION

This invention relates to a relay used with a voltage regulator and more in particular to an improved construction of a two-contact relay for the voltage regulator used mainly with the charging device such as the generator of a powered vehicle.

BRIEF DESCRIPTION OF THE DRAWING

FIG. 1 is a plan view of a prior art relay.

FIGS. 2A and 2B are plan and side views, respectively, showing portions including an armature and spring of the relay shown in FIG. 1.

FIG. 3 is a front sectional view showing the essential parts of an embodiment of the relay according to the present invention.

FIG. 4 is a side view showing the relay according to the present invention.

FIG. 5 is a sectional view showing the essential parts of another embodiment of the movable iron piece used in the relay according to the present invention.

DESCRIPTION OF THE PRIOR ART

The well-known prior art voltage regulator relay of this kind has the construction as shown in FIGS. 1 and 2, which requires two types of adjustment of the setting voltage for voltage regulation. Firstly, in order to adjust the magnitude of the voltage for actuating its armature 5, the force of the first spring 8, which works against the attractive force of the iron core 2 wound with the voltage coil 1 and the armature 5 attracted to the iron core 2, is changed by bending the adjusting protrusion 3 upward or downward. Secondly, at low vehicle speeds when the generator voltage is relatively low, the voltage regulation is achieved by vibratory operation for opening and closing alternately between the contact 12 and movable contact 6, whereas at high vehicle speeds when the generator voltage is relatively high, the contact 13 and movable contact 6 are alternately connected and disconnected to regulate the voltage. In this case, it is necessary to achieve the same effect of the voltage regulation at both high and low vehicle speeds, and in order to achieve this purpose, as shown in FIG. 2, the aperture 9a for fixing the spring 9 on the armature 5 is made in the form of an elongated slot so that the armature 5 is movable in the direction of X - X' relative to the yoke 4 by loosening the fastening screw 11', or the gap g between the armature 5 and yoke 4 is changeable by bending the contacts 12 and 13 in the direction X - X'. These two types of adjustment of the setting voltage, however, affect each other and hence the adjustment must be repeated many times before a desired setting voltage is obtained. For this reason, it is impossible to conduct the adjustment while the relay is in operation. Further the adjustment itself requires a high skill because the setting voltage is incapable to be determined as a monotone function of either one of the two types of adjustment.

SUMMARY OF THE INVENTION

An object of the present invention is to provide a very useful relay for a voltage regulator capable of easy and accurate adjustment of the setting voltage for voltage regulation without changing the position of the armature and the contacts by providing a movable iron piece to effectively change the gap between the arma-

ture and yoke, whereby the problems, as mentioned with reference to the conventional relay, are solved.

Another object of the present invention is to provide a relay for a voltage regulator comprising an iron core 5 wound with voltage coils, an armature with a movable contact adapted to be attracted to said iron core, a yoke supporting said armature and combining with said iron core and armature to constitute a magnetic circuit, a movable contact of said armature, said movable contact being adapted to be connected and disconnected to a contact for controlling the output voltage of the generator at low vehicle speeds and to another contact for controlling the same at high vehicle speeds, and a movable iron piece for effectively changing the gap between said armature and said yoke.

According to the present invention, the yoke is provided with a movable iron piece for effectively changing the gap between the yoke and the armature. As a result, there is no need to move either the armature or the contact to change the gap between the yoke and armature, making possible such adjustment that the setting voltages for voltage regulation at both high and low vehicle speeds agree with each other very easily.

DESCRIPTION OF THE PREFERRED EMBODIMENTS

The device according to the present invention will be now explained with reference to the embodiments shown in the attached drawing. In FIGS. 3 and 4, the reference numeral 1 shows voltage coils, numeral 2 an iron core wound with said coils and integrated with a protrusion 3, and 4 a yoke so shaped as to have at its top and bottom bent portions 4a and 4b respectively adapted to extend in opposite directions, said iron core standing upright on the bottom bent portion 4b. The numeral 5 shows an inverted-L shaped armature with one end opposed to the iron core 2 and the other end provided with the movable contact 6. The first and second springs 8 and 9 are fixed on the armature 5 at its bent portion by means of the rivet 7. The first spring 8 has a free end supported by the protrusion 3, while the other end of the second spring 9 with a couple of holding plates 10 on the upper and lower sides thereof is fixed on the bent portion 4a of the top of the yoke 4. The numeral 12 shows a contact for controlling the output voltage of the generator at low vehicle speeds, and numeral 13 a contact for controlling the output voltage of the generator at high vehicle speeds, both of the contacts being opposed to each other with a movable contact 6 between them. The numeral 14 shows a fan-shaped movable iron piece with teeth 14a on its periphery, which is rotatably mounted on the yoke 4 by means of the rivet 15 between the yoke 4 and the armature 5. The teeth 14a of the movable iron piece 14 are projected sideway from the yoke 4 for providing means for rotating the movable iron piece 14 around the rivet 15 thereby to change the area of the movable iron piece interposed between the yoke 4 and the armature 5.

Explanation will be made now of the operation of the relay with the above-described construction according to the present invention. When a voltage is applied to the voltage coils 1, a magnetic flux is generated in a magnetic circuit consisting of the iron core 2, yoke 4 and armature 5 as much in accordance with the magnitude of the voltage applied, whereupon, as the applied voltage exceeds a pre-determined value the armature 5

is attracted to the iron core 2 by the attractive force generated between the armature 5 and the combination of the iron core 2 and the yoke 4, resulting in the movable contact 6 disconnecting from the contact 12.

The voltage regulation is achieved by connecting and disconnecting alternately the movable contact 6 with the contact 12 at low vehicle speeds and with the contact 13 at high vehicle speeds thereby reducing a current supplied to a filed winding (not shown) of the generator to regulate the voltage thereof.

By rotating the movable iron piece 14, it is possible to equalize the regulated voltage obtained by the cooperation between the contacts 6 and 12 for low vehicle speeds and that obtained by the cooperation between the contacts 6 and 13 for high vehicle speeds. Thus when the movable iron piece 14 is rotated in the direction of θ or θ' using a screw driver or the like tool, the area of the movable iron piece inserted between the yoke 4 and armature 5 is increased or decreased as the case may be. When the movable iron piece 14 is inserted between the yoke 4 and armature 5, the magnetic gap between the yoke 4 and the armature 5 is in effect replaced by the magnetic gap between the movable iron piece 14 and armature 5. In consequence, by controlling the area of the movable iron piece inserted between the yoke 4 and the armature 5, the same effect is achieved as if the gap between the yoke 4 and the armature 5 is adjusted.

Although in the embodiment shown above a fan-shaped magnetic plate with the teeth 14a is used as the movable iron piece 14 and is rotatably mounted on the yoke 4, the yoke may be provided with a groove in the upward direction to receive slidably a movable iron piece of magnetic material in the form of plate tapered, as desired, in the direction of width or thickness. As another possibility, the yoke 4 may be provided with an internally threaded hole 4c as shown in FIG. 5 into which the movable iron piece of magnetic material consisting of the screw 14' is fitted so that the gap between the leading end of the screw 14' and the armature 5 may be controlled by turning the screw 14' with a screw-driver or the like tool applied to the recess 14'a.

I claim:

1. A relay for a voltage regulator comprising: an iron core wound with voltage coils, an armature with a movable contact adapted to be attracted to said iron core, a yoke supporting said armature and combining with said iron core and armature to provide a magnetic circuit, a movable contact of said armature, said movable contact being adapted to be alternately connected and disconnected to a contact for low vehicle speeds and a contact for high vehicle speeds, and a movable iron piece for changing the gap between said armature and said yoke such that the difference between the voltage to open and close the contacts for the high speed

operation and the voltage to open and close the contacts for the low speed operation may be reduced in changing the former voltage much more than the latter voltage.

5 2. A relay according to claim 1, in which said movable iron piece comprises a plurality of teeth formed on the periphery thereof and projected sideway from said yoke, said teeth being utilized to rotate said movable iron piece around a rivet, whereby the area of said movable iron piece inserted between said yoke and said armature is changed.

10 3. A relay according to claim 1, in which said yoke is provided with an internally threaded hole fitted with a movable iron piece consisting of a screw of magnetic material, said screw being operated to change the gap between said armature and said yoke.

15 4. A relay for a voltage regulator of a vehicle, including:

an iron core and voltage coils wound thereabout; an armature adapted to be attracted to said iron core upon energization of said voltage coils;

a yoke supporting said armature for providing a magnetic circuit with said iron core, said relay including a movable contact mounted to a free end of said armature and two contacts adapted to engage with the movable contact, said movable contact assuming one position engaging with one of said contacts when the voltage coils are energized to a selected voltage indicative of a low engine speed of the vehicle, and a second position engaging with the other of said contacts upon energization of the voltage coils to a selected voltage indicative of high engine speed, and movable means fixed to the yoke interposed spatially in an air gap of the armature to adjust the size of the air gap, such that the selected voltages are substantially equal, providing a voltage regulation of the relay whereby the movable contact switches in and out of engagement with its fixed contact at substantially the same voltage for both high and low engine speeds.

5. The relay as described in claim 4 wherein said means for adjusting the air gap comprises:

a movable iron piece including a plurality of teeth formed in the periphery thereof and projected sideways from said yoke, said teeth being utilized to rotate said movable iron piece around a rivet, the area of said movable iron piece inserted between said yoke and said armature to change the air gap.

45 6. A relay as described in claim 5, wherein said movable iron piece is wedge shaped so as to adjust the air gap when moved selectively.

50 7. A relay described in claim 4, wherein said yoke is provided with an internally threaded and a movable iron piece fitted therein comprising, a screw of magnetic material, said screw being operated to change the air gap between said armature and said yoke.
